US00D815116S

(12) **United States Design Patent** (10) Patent No.: **US D815,116 S**
(45) Date of Patent: **** Apr. 10, 2018**

(54) **DISPLAY SCREEN OR PORTION THEREOF WITH GRAPHICAL USER INTERFACE**

(71) Applicant: **salesforce.com, inc.**, San Francisco, CA (US)

(72) Inventor: **Adrian Dieter Rapp**, Sausalito, CA (US)

(73) Assignee: **salesforce.com, inc.**, San Francisco, CA (US)

(**) Term: **15 Years**

(21) Appl. No.: **29/589,775**

(22) Filed: **Jan. 4, 2017**

Related U.S. Application Data

(63) Continuation of application No. 29/579,969, filed on Oct. 4, 2016.

(51) **LOC (11) Cl.** **14-04**

(52) **U.S. Cl.**

Primary Examiner — Robin V Webster

Assistant Examiner — Rachel Voorhies

(74) Attorney, Agent, or Firm — Sterne, Kessler, Goldstein & Fox PLLC.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost dashed broken lines in the FIGURE show a display screen or portion thereof, and form no part of the claimed design. The other broken lines in the FIGURE show portions of the graphical user interface that form no part of the claimed design.

1 Claim, 1 Drawing Sheet
